UNITED STATES PATENT OFFICE.

GEORGE M. ATCHISON, OF WEST TROY, NEW YORK, ASSIGNOR OF ONE-HALF
TO JOHN PICKEN, OF SAME PLACE.

WEFT STOP MECHANISM FOR LOOMS.

SPECIFICATION forming part of Letters Patent No. 400,159, dated March 26, 1889.

Application filed January 3, 1889. Serial No. 295,312. (No model.)

To all whom it may concern:

Be it known that I, GEORGE M. ATCHISON, a resident of West Troy, in the county of Albany and State of New York, have invented 5 certain new and useful Improvements in Weft Stop Mechanisms for Looms; and I do hereby declare that the following is a full, clear, and exact description of the invention that will enable others skilled in the art to 10 which it appertains to make and use the same, reference being had to the accompanying drawings, and to the letters of reference marked thereon, which form a part of this specification.

15 Similar letters refer to similar parts in the several figures therein.

My invention relates to improvements in weft stop-motion for looms; and it consists of the novel construction and combination of 20 parts hereinafter described, and pointed out in the claim.

Figure 1 of the drawings is a view in front elevation of a portion of the breast-beam and frame, showing a portion of the shipping 25 mechanism. Fig. 2 is a vertical cross-section taken at broken line xx in Fig. 1, showing partly in dotted lines the frame and lay and the stop-motion mechanism in the relative positions occupied while the loom is at work. 30 Fig. 3 is a view similar to that seen in Fig. 1, showing the relative position of the parts when the belt has been shipped to the idle-pulley. Fig. 4 is a view similar to that seen in Fig. 2, showing the relative position of the 35 parts after they have actuated the belt-shipper. Fig. 5 is a view in side elevation of the cam-rammer detached. Fig. 6 is a view in front elevation of the rammer-trip detached. Fig. 7 is a plan view of the parts 40 shown in Figs. 2 and 4 occupying the relative position shown in Fig. 2.

I have only shown such parts of the loom as are necessary to a proper understanding of my improved mechanism for stopping the 45 loom when the weft breaks or fails to be properly thrown.

A is the breast-beam, and A' a portion of the frame of the loom.

A^2 is the lay supported and actuated in any 50 known manner, as by lance A^3 , crank-wheel

A^4 , and pitman A^5 . (Shown by dotted lines in Fig. 2.)

The lay is provided with a transverse slot, A^6 , adapted to receive the fingers B , projecting from the lever-arm B' . The fingers and 55 arm together form a lever of the third class, fulcrumed at one end upon the pivot B^2 , passing through the ears B^3 , projecting from a casting, B^4 , secured to the lay, as by screws B^5 .

Power is applied to the lever through the 60 trip B^6 , one end of which is provided with ears B^7 , pivoted to the lever intermediately of its ends, while the other end, terminating in a head, B^8 , is movable in a slideway formed in the arm B^9 , projecting from the casting. 65

Secured to the breast-beam is an angle-arm, C , adapted to support the rammer C' , which consists of a rod or bar of iron provided with a slot, C^2 , extending longitudinally of the bar and in a direction diagonal thereto. 70 One end of the rammer is provided with a guiding-slideway in the vertical arm C and terminates in a head, C^3 . The other end of the rammer is supported and guided by a pin, C^4 , passed through the ears C^5 on the 75 horizontal arm C and the slot C^2 . The horizontal arm is provided with a slot, C^6 , adapted to receive the rammer, as shown in Fig. 7, and indicated by dotted lines in Fig. 4. The extreme end of the horizontal arm is provided with a block, C^7 having an inclined 80 slideway, C^8 . The breast-beam also supports a cam-lever, D , secured thereto by the pivot D' . The head of the rammer and cam are relatively so situated that the former, when 85 energized, will actuate the arm D^2 of the cam-lever, while the arm D^3 is made thereby to engage with a stop, D^4 , fixed upon the slide-bar D^5 and move the belt-shipper F from fixed pulley F' to loose pulley F^2 , as indicated by 90 dotted lines in Fig. 7 and shown by solid lines in Fig. 3.

D^6 is a hand-lever pivoted upon the frame and secured to the slide-rod D^5 , by means of which the belt-shipper can be moved to 95 change the belt F from one pulley to the other.

G is the weft-yarn, which has been thrown upon the bed-plate A^7 of the lay by the shuttle and across the slot A^6 .

The operation of the device is as follows: As the lay moves forward from the position shown in Fig. 2 to that shown in Fig. 4, the trip B⁶ slides down the incline C⁸ until the fingers B strike the yarn, as shown by the upper dotted lines in Fig. 4. The yarn holds the trip up to a level just above the contiguous end of the rammer, and it rides over the same without contact with it. When the lay is carried back to the position shown in Fig. 2, the trip slides up the incline C⁸, thereby lifting the fingers from the lay to the position shown by the solid lines in Fig. 2, to permit the shuttle to move freely between the fingers and the bed-plate A⁷ of the lay; but if from any cause the weft-yarn G should break or miss being properly thrown upon the lay across the slot A⁶, then the trip would slide down the incline C⁸ until the ends of the fingers reached the bottom of slot A⁶, or the position shown by the lower dotted lines in Fig. 4, which would permit the head of the trip to fall to the level of the contiguous end of the rammer and engage with the same to cause it to partake of the forward movement of the lay, causing it to move from the position shown in Fig. 2 to that shown in Fig. 4, and from the position shown by the solid lines in Fig. 7 to that shown by the dotted lines in the same figure, thereby acting through cam-lever D and stop D⁴ to ship the belt from the fixed to the loose pulley and stop the loom. The slot in the rammer is so located and shaped that when the rammer has been carried far enough to ship the belt it drops down out of reach of the trip, and the latter, after breaking its engagement therewith, is free to travel any desired distance beyond the end of the rammer without any influence upon it, as shown in Fig. 4, the

higher portion of the slot sliding down to a 40 level with the supporting-pin, C⁴. The rammer, cam-lever, and shipping slide-rod are forced back into the position shown in Fig. 2 by the hand-lever D⁶ when the loom is started again, after being automatically stopped by 45 my improved mechanism.

I am thus able with simple and easily-constructed mechanism, which can be easily attached to the various forms of looms now in use, to positively stop the loom whenever the 50 weft breaks or is unable to prevent the fingers from falling into the slot A⁶.

I make no use of springs and secure positive movements of parts which are easily operated and not likely to get out of order. 55

What I claim as new, and desire to secure by Letters Patent, is—

In a loom, the combination, with a shipping mechanism, of the lay provided with a cross-slot, fingers B, having one end pivotally secured to the lay, and the other ends movable in and out of the cross-slot, trip B⁶, pivotally secured to the fingers intermediately of their ends and vertically movable in a slide-way secured to the lay, an inclined slideway, 60 C⁸, for the trip, rammer C', having a diagonal slot and supported at one end by a pin passing through such slot, and a rammer engaging lever-cam pivotally secured to the breast-beam, and a cam-engaging stop fixed upon 70 the shipper-actuating slide-rod, substantially as described.

In testimony whereof I have hereunto set my hand this 29th day of December, 1888.

GEORGE M. ATCHISON.
